UNITED STATES PATENT OFFICE

2,568,704

BRAKE HANGER

Walter H. Baselt, Flossmoor, Ill., assignor to
American Steel Foundries, Chicago, Ill., a corporation of New Jersey

Application January 28, 1949, Serial No. 73,280

7 Claims. (Cl. 188—206)

1

This invention relates to railway brake equipment and more particularly to novel means for controlling certain oscillations of the brake hangers which experience has proved are particularly destructive to the hangers and associated brake rigging.

A general object of the invention is to provide a control assembly between the hanger and its support to snub certain movements of the hanger and thus prevent free swinging of the brake rigging.

Another object of the invention is to provide an assembly which may be readily incorporated in brake equipment presently in use.

The preferred embodiments of the invention contemplate the provision of a control arm which is separate from the hanger whereby a conventional hanger may be used in the rigging, and further contemplates the provision of a flexible connection between the support and arm, the latter being arranged to engage the hanger during certain movements thereof to yieldingly resist such movements.

A further object of the invention is to provide a simple inexpensive and effective control means which may be easily assembled and disassembled with respect to the brake equipment.

These and other objects of the invention will become more apparent from the specification and the drawings, wherein:

Figure 1 is a front view of an assembly incorporating one form of the invention, with parts shown in transverse vertical section;

Figure 2 is a sectional view taken on the line 2—2 of Figure 1;

Figure 3 is a view similar to Figure 1 illustrating another form of the invention;

Figure 4 is a sectional view on the line 4—4 of Figure 3; and

Figure 5 is a view comparable to Figure 1, illustrating a further modification of the invention.

Describing the invention in detail and referring first to the preferred embodiment as shown in Figures 1 and 2, the hanger 2 may be of conventional form comprising a shank or body portion 6 intermediate its ends and heads 8 and 10 at opposite ends thereof. The head 8, located at the lower end of the hanger, is provided with a bushed opening 12 affording a usual means of connection to an associated brake part, such as a brake beam.

The head 10 at the upper end of the hanger is received between a pair of spaced substantially parallel lugs 14 and 16 of a support bracket 18, which may be an integral part of the associated

2

truck frame (not shown), as will be readily understood by those skilled in the art. The hanger is pivotally connected to the bracket by a pin 20 which extends through aligned openings in the head 10 of the hanger and in the bracket lugs 14 and 16. The ends of the pin project outwardly beyond the remote sides of the lugs 14 and 16 and the pin is secured to the support bracket by a nut assembly 22 threaded on one end of the pin and abutting against the external side of lug 16, and an enlarged abutment portion 24 at the other end of the pin drawn against the external side of the lug 14 by tightening the nut 22.

The portion 24 is cylindrical and extends through an opening 26 in the upper end of a control arm or lever 28 to afford a pivotal mounting therefor on a common axis with the hanger. The lower part of the control arm is bent or curved toward the hanger and the lower extremity thereof is provided with a generally vertical U-shaped slot 30 which receives or extends around a portion of the shank 6 of the hanger. A non-metallic material, such as brake lining 32, is interposed between the sides of the slot and the hanger, said material being secured to the adjacent portions of the arm in any convenient manner as by rivets 34. The arm engages the forward and rear and a lateral side of the hanger and is movable with the hanger during rotation of the hanger in its normal plane on the pin and also during movement of the hanger laterally toward the control arm. The lining 32 serves to cushion impacts between the hanger and the control arm and reduces wear therebetween.

The arm is yieldingly restrained against movement by spaced resilient units 36 and 38, sleeved on the enlarged portion 24 of the pin at opposite sides of the control arm. Each unit comprises a pad of resilient material 40, such as rubber, interposed between spaced washers and vulcanized thereto. The unit 36 is compressed between and engages as at 42 the external side of lug 14 and as at 44 the adjacent side of arm 28, and unit 38 is compressed between and engages as at 46 a head 48 on the adjacent end of the bolt and as at 50 the adjacent side of the control arm. The arm is movable axially of the bolt and compresses pad 38 when the hanger swings or moves laterally toward the arm. After some wear in the opening 26, as shown, the arm when moved laterally by the hanger cant on an axis transversely of the bolt and compresses both units or pads 36 and 38. It will be understood that lateral swinging of the hanger will generally occur after some wear

between the hanger and the pin, as shown in the bushed opening 52 in the head 10 and initially such movement is accommodated by manufacturing tolerances which do not provide for a tight fit of the pin in opening 52. The control arm also resists pivotal or rotational movement of the hanger in its normal plane about the bolt by stressing the resilient units in shear. This action is helpful in releasing the brakes, as will be readily understood by those skilled in the art.

In brake equipment of the type under consideration, the hangers at opposite sides of the truck are interconnected by beams (not shown) and the arms associated with respective hangers control the movement thereof laterally in different directions whereby their movement in both directions laterally is restrained.

Referring now to the second embodiment of the invention as illustrated in Figures 3 and 4, the structure is similar to the previous embodiment and like parts are identified by identical reference numerals. In the present modification the lower end of the control arm or lever 28 is enlarged laterally to provide a seating portion or abutment 100 adjacent one side of the shank 6 of the hanger and a nonmetallic material 102, such as brake lining, is secured to the seating portion 100 in any convenient manner, as by rivets 106, the lining being engageable with the hanger upon movement of the hanger laterally toward the arm. The upper end of the arm, as in the previous embodiment, is sleeved onto the enlarged portion 24 of the pin 20 and is urged against the outer side of the lug 14 by a resilient unit 108, identical with units 36 and 38, and compressed between the head 48 of the bolt as at 110 and the control arm or lever as at 112. The portion 24 as in the previous embodiment prevents overcompression of the resilient unit as it is initially compressed by tightening the nut 22, the portion 24 abutting lug 14.

Figure 5 illustrates the third embodiment of the invention and comprises a hanger 200 with a bifurcated upper portion forming spaced legs 202 and 204 arranged in side-by-side relationship and spaced laterally with respect to each other. The leg 202, which is part of the hanger proper, is received between spaced lugs 206 and 208 of a bracket 210 which may be part of the truck frame. The leg 202 is pivoted on a pin or bolt 212 which extends through aligned openings in the spaced lugs 206 and 208 and opening 214 in leg 202. The pin comprises a nut assembly 216 at one end and a cylindrical head 218 at its opposite end which engage the remote sides of the lugs 206 and 208, respectively. The other leg, arm or lever portion 204 of the hanger comprises an opening 220 through which extends a cylindrical head 218 of the pin for pivoting the control arm 204. The hanger and the control arm are thus afforded a pivot at spaced points on a common axis on the pin 212. The play between the hanger and the pin is reduced and the hanger is afforded a novel two-point support. Lateral swinging of the hanger is reduced by abutment of portions 202 and 204 with the pin.

It will be understood that in all three embodiments, the lateral swinging of the hanger is controlled by an arm or lever, which in certain embodiments is flexibly connected to the pin and support. All of the embodiments are easy to assemble and disassemble, are effective to control or reduce lateral swinging of the hangers, and are useable with existing brake equipment since no changes in the support brackets is required.

I claim:

1. In a brake arrangement, a support comprising spaced depending lugs, a hanger having an end interposed between the lugs, pivot means extending through said lugs and said end of the hanger affording a pivotal connection between the hanger and support, abutment means at opposite ends of said pivot means disposed adjacent the remote sides of said lugs and in engagement therewith, one of said abutment means being of cylindrical form and engaging the adjacent lug along a surface extending transversely of said pivot means, a head on said abutment means spaced from the adjacent lug, a control arm pivoted at one end on said one abutment means and in frictional engagement at one side with said surface, a resilient bushing sleeved onto said one abutment means between said head and the other side of said arm and in engagement therewith and compressed therebetween axially of said pivot means, and nonmetallic lining material on the other end of said arm engaging said hanger at an area intermediate the ends thereof.
2. In a brake arrangement, a support, a nut and bolt assembly extending through said support, abutment means at opposite ends of said assembly tightly engaging oppositely facing surfaces of the support, a control arm pivoted at one end on one of said abutment means, a hanger pivoted at one end on said assembly between said surfaces, resilient means mounted on said abutment means and compressed axially of said assembly against said arm, and nonmetallic lining carried by the other end of said arm in engagement with the hanger, said hanger being movable longitudinally of the control arm whereby loading of the hanger will not load the arm.
3. In a brake arrangement, a support comprising spaced lugs, a pivot element extending through said lugs, abutment means at opposite ends of said element tightly engaging the remote sides of said lugs, a hanger pendulously suspended at one end from said element between said lugs, a head integral with one of said abutment means and spaced axially of said element outwardly of the adjacent lug, a control arm pendulously suspended at one end on said one abutment means between said head and the adjacent lug, resilient means mounted on said one abutment means and compressed against said arm axially of the element, said resilient means including a rubber bushing between the head and arm and in engagement therewith, and a nonmetallic lining on the other end of said arm engaging said hanger in an area intermediate the ends thereof.
4. In a brake arrangement, a support comprising spaced lugs, pivot means extending through said lugs and having abutment means tightly engaging the remote sides of said lugs, a hanger pendulously suspended at one end from said pivot means between said lugs, a control member pendulously suspended at one end from one of said abutment means, resilient means mounted on said one abutment means and compressed against said arm to restrain movements thereof, and nonmetallic lining on the other end of said arm extending a substantial distance forwardly and rearwardly of said hanger in an area intermediate the ends thereof for flat face abutment therewith, said hanger being rotatable in a plane parallel to said face without actuating said arm, said hanger in moving angularly to said plane against said face being effective to actuate said arm and stress said resilient means.

5. In a brake arrangement, a support, a pivot element having spaced abutments, spaced lugs on said support connected to said element between said abutments and disposed one adjacent each abutment in engagement therewith, a hanger pendulously suspended from said element between said lugs, a control arm at one side of the hanger pendulously suspended at one end from one of said abutment means, resilient means mounted on said last-mentioned abutment means and formed and arranged to be stressed by said arm during movements thereof, a jaw at the other end of said arm extending around said one side of the hanger and the opposite sides of the hanger adjacent thereto, and a non-metallic lining within the jaw engaging said sides of the hanger.

6. In a brake arrangement, a support, pivot means carried thereby, a hanger pendulously suspended from said pivot means, a control arm at one side of said hanger pendulously suspended at one end from said pivot means, resilient means operatively associated with said pivot means and disposed to engage at least one side of said arm and to be stressed by said arm during movements thereof, and means at the other end of said arm adapted for abutment with said hanger intermediate the ends thereof during certain move-

ments of the hanger, said hanger being movable longitudinally of the control arm whereby loading of the hanger will not load the control arm.

7. In a brake arrangement, a support, a hanger, a control arm, pivot means rotatably connecting one of the ends of said hanger and arm to said support, resilient means carried by said pivot means and operatively associated with said arm to yieldingly resist movements thereof, and means slidably connecting the other end of said arm with said hanger for movement longitudinally of the hanger.
